UNITED STATES PATENT OFFICE.

AXEL MORCK, OF NEW YORK, N. Y.

HORSESHOE.

1,250,484.

Specification of Letters Patent. Patented Dec. 18, 1917.

Application filed February 4, 1915, Serial No. 6,091. Renewed May 3, 1917. Serial No. 166,276.

To all whom it may concern:

Be it known that I, AXEL MORCK, a citizen of Sweden, and resident of the borough of Bronx, in the county of Bronx and State of New York, have invented certain new and useful Improvements in Horseshoes, of which the following is a specification.

This invention relates to improvements in farriery, and is generally applicable to shoes worn by solipeds, of the genus *Equus*, including the domestic horse and other solid-ungulate species of the same genus. In a more restricted sense, the invention has particular reference to a horseshoe provided with removable toe and heel calks.

One of the objects of the invention is to produce an improved horseshoe having separable calks, both at the toe and heel, that can be easily detached for sharpening when dulled from any cause, or else replaced by new ones if too much worn out to be renovated.

A further object is to provide simple means, readily operable by horsemen or teamsters, whereby they will be enabled personally to take off the calks of a shoe with the aid of common tools, and securely reinsert or replace the same after removal.

Another object is the production of a shoe of the character set forth which shall be amenable to the ordinary process of drop-forging, and therefore will not involve machine work or special fitting to complete it, thus affording a low-priced article scarcely exceeding in cost that of the prevalent type of horseshoe with calks integrally formed.

Still another object is the provision of a comparatively light horseshoe, the weight whereof, including its detachable accessories, will closely approximate or not materially differ from that of the solidly calked shoe now in common use for the same purpose.

Other objects and advantages of the invention will become apparent as the specification proceeds.

With the aforesaid objects in view, the invention consists of the improved combinations of parts hereinafter described in their preferred embodiments, pointed out in the subjoined claims, and illustrated in the annexed drawing, wherein—

Figure 1 is a bottom plan view of a horseshoe constructed in accordance with the present invention, parts thereof being shown in section, taken on the line 1—1 of Fig. 3;

Fig. 2 is an outer edge view of the for-

ward part of the same, looking from the left-hand side of Fig. 1;

Fig. 3 is an inner edge view of one half of the shoe, with the calks and adjacent parts in section;

Fig. 4 is a transverse section on the line 4—4 of Fig. 3; and

Fig. 5 is an end elevation of one of the heel calks pertaining to the invention, as the same appears previously to being given the form represented in Fig. 4.

In these views, the numeral 11 denotes the under or bottom face of the quarters or side portions of a horseshoe, having the customary fullering or creases 12, with nail-holes 13.

At the front or toe part, the shoe is formed on the under side with a straight or plane face 16, lying at a somewhat higher level than the bottom edges 17 of the said quarters 11, in the said part of the shoe, which is made thicker or deeper from the top down, forward, as shown. In other words, the straight or plane face 16 is of substantially the same thickness as the rear portions of the quarters, but is bounded laterally by inclines 17, projecting downwardly on each side thereof and forming opposite abutments, as indicated in Figs. 2 and 3.

From the inner and outer edges, respectively 18 and 19, of the straight face 16, the front or toe part of the shoe is beveled upwardly and inwardly in dovetail formation, as shown at 20, Fig. 3. The slanting faces 21 and 22 thereby formed are of similar inclination, excepting the upper margin of the front face 21, which is offset forwardly as at 23, for a purpose that will hereinafter clearly appear.

The toe calk proper, designated by the reference numeral 26, is preferably formed integral with a plate or backing 27, the full cross section whereof is shown shaded in Fig. 2 and is proportioned to fit snugly between the straight inner edges of the before-mentioned inclines 17, which serve to hold it positively against lateral displacement. Front and rear jaws 28, 29 extend upwardly from the said plate 27 and calk 26 thereunder, and are given the same inclination as that of the aforesaid faces 21, 22 of the front portion 20 of the shoe, barring the said margin or offset 23. The front jaw 28 is spaced away a certain distance from the front face 21, and has its inner surface 30 beveled off,

as seen in Fig. 1, with relation to the latter-named face. A wedge key 31, having its outer side conforming to the obliquity of the surface 30, is driven into the space intervening between the latter and the face 21 of the part 20. The upper flat surface of the plate 27 and the inner face of the rear jaw 29 are thereby drawn forcibly into contact with the underside or straight face 16 and the rear edge 22, respectively, of the front part 20 of the shoe.

The breadth of the said key 31, measured from front to rear, and the drawing action thereby exerted hold the front jaw 28 of the plate 27 from sagging or slipping down. The thin end or point 32 of the key is bent over the edge of the jaw 28, when it has been driven in as far as it will go, to preclude disassociation of the conjoined parts. The upper inner edge of the key finds lodgment in the obtuse angle formed by the inclined front face 21 of the dovetail section 20 of the shoe and the vertical edge 23 of the latter, and is thereby prevented from creeping up and out of place.

The upper portion of the front jaw 28 may be carried up above the top face 33, to form a removable clip 34, which can be hammered to conform to the point of a horse's hoof, analogously to what was done heretofore with the ordinary horseshoe.

As indicated particularly in Figs. 1 and 4, the rear end of the shoe is dovetailed in two directions, to wit, longitudinally of the quarters, with the taper increasing rearward, as at 37, and transversely, after the manner of the front section 20, that is with upwardly and inwardly beveled sides 38, 39, the exterior one of which is formed with a straight portion 40 similar to the flattened margin 23 of the said front section 20 and provided for a like purpose.

A removable heel calk 41, depending from a plate or backing 42, is attached to the rear end 37 of the shoe. The plate or backing 42 is formed with jaws 43 and 44, the latter of which is on the outside of the shoe and spaced from the said beveled side 38, so that a wedge key 45 can be driven therebetween. The forced insertion of this key draws the upper surface 46 of the heel-calk plate 42, as also the jaw 43 thereof, solidly against the under side 11 of the shoe and the beveled side 39 of the rear section 47, respectively. To hold the key from working out, the end 48 thereof may be bent over the adjoining edge of the jaw 44, as represented in Fig. 1.

Longitudinal displacement of the rear calk-plate 42, relatively to the end section 47, is guarded against by forming in the latter a recess or cavity 49, adapted to be engaged by a ridge or protuberance 50, struck up from the inner face 46 of the said plate 42.

The said heel calk is drop-forged with the

jaws 43, 44 thereof straight or perpendicular to the face 46, as represented in Fig. 5, so that its several angles and corners will readily leave the die in which it is made. The heel calk having been formed in the manner indicated, the jaws thereof are subsequently forced to assume the shape illustrated in Fig. 4. It is understood that the narrowest opening is left between the lips of these jaws to permit the heel calk to be slipped over the flaring base of the shoe section 47.

Although no separate illustration of the toe calk has been given, it is obvious that the same process is followed in forming the slanting jaws of the latter as for those of the heel calk.

It will further be understood that, notwithstanding the square heel calk 53 pertaining to the inner half of the shoe has been shown as being formed solid therewith, obviously it is within the scope of the invention to make this calk on the same order as the sharp-pointed outer heel-calk 41.

Having described my invention, what I desire to secure by Letters Patent and claim is:—

1. A horseshoe having a toe portion formed with a substantially plane under face, a detachable calk-bearing plate secured to said toe portion, and abutments by the longitudinal sides of said plate inclined away from the same in opposite directions toward the bottom face of the shoe's side portions.

2. A horseshoe including a toe with oppositely inclined portions on the under side thereof, a dovetailed section of less thickness intermediate of said inclined portions, a calk-bearing plate, and clasping means of corresponding shape to said section serving to hold said plate thereon in firm position.

3. A horseshoe comprising a dovetailed member having a marginal projection on the front side thereof, a calk-bearing plate provided with jaws set at inclines conforming to the opposite front and rear sides of said member, and a wedge key insertible between one of said jaws and the adjacent side of the member under said marginal projection.

4. A horseshoe comprising an externally dovetailed toe portion, a calk-bearing plate embracing the same, jaws on said plate rising on opposite sides of said toe portion with their inner faces inclined to correspond with said toe portion, a clip on one of said jaws, and means acting against the outside face of the toe portion operating to draw the other jaw in contact with the inner face thereof.

5. A horseshoe having a portion formed with an approximately straight under face, inclined edges extending upwardly from the front and rear thereof, abutments depending from the sides of said portion, and a calk-bearing plate removably received between said abutments and clasping said inclined edges.

6. A horseshoe including a flat portion in its under side, oppositely tapered faces extending upwardly from two edges of said flat portion, substantially perpendicular faces 5 constituting abutments depending from the other edges of said portion, a detachable calk-bearing plate having a plane upper part with inclined jaws at the ends thereof and provided with straight side edges, the latter 10 being received between said abutments, and means for drawing the upper part of said plate against the under side of the flat portion on the shoe, with a jaw in contact with one of the tapered faces and the other jaw 15 spaced away from the other tapered face.

7. A horseshoe comprising a substantially plane portion formed on the under side thereof, inwardly slanting faces extending upwardly from opposed edges of said plane 20 portion, one of said faces having a forwardly

offset marginal projection, abutments depending from adjacent edges of said portion, a calk-bearing plate including a flat upper part carrying beveled jaws removably received between said abutments, and a wedge 25 key driven intermediately of one jaw and one of the slanting faces so as to draw the flat part of the plate against the plane portion of the shoe and with the other jaw in contact with the oppositely slanting face, 30 said key having one edge lodged against said marginal projection to prevent it from working out.

Signed at the borough of Manhattan in the county of New York and State of New 35 York this 23rd day of January A. D. 1915.
